OTHER PUBLICATIONS

Attached are drawings of a container having three compartments, which is available in the marketplace ("Other Container"). The drawings present a perspective view and a top

plan view of the Other Container and show, among other differences, the difference in the size, shape, and placement of the individual compartments as compared to those in the Applicant's design.

Primary Examiner—Ted Shooman

Assistant Examiner—Nanda Bondade

CLAIM

The ornamental design for a three-compartment container, as shown and described.

DESCRIPTION

FIG. 1 is a perspective view of a three compartment container showing inventor's new design;

FIG. 2 is a top plan view thereof;

FIG. 3 is a rear view thereof;

FIG. 4 is a front view thereof;

FIG. 5 is a left side view of FIG. 2;

FIG. 6 is a right side view of FIG. 2;

FIG. 7 is a bottom plan view of FIG. 1;

FIG. 8 is a sectional view of said three-compartment container as indicated in FIG. 2; and,

FIG. 9 is a sectional view of said three-compartment container as indicated in FIG. 2.
